Edward L. Morris.

UNITED STATES PATENT OFFICE.

EDWARD L. MORRIS, OF BOSTON, MASSACHUSETTS.

DESIGN FOR A TABLE-BELL.

SPECIFICATION forming part of Design No. 13,012, dated June 27, 1882.

Application filed March 27, 1882. Term of patent 7 years.

To all whom it may concern:

Be it known that I, EDWARD L. MORRIS, a citizen of the United States, residing at Boston, in the county of Suffolk and State of Massachusetts, have invented and produced a new and original Design for Table-Bells, of which the following is a specification, reference being had to the accompanying drawing, forming part thereof.

10 My design consists in the representation of an equine animal standing underneath a table-bell; further, in the representation of an owl surmounting the bell; and, further, in forming the hammer of a table-bell to represent an equine animal whose heels kick up to hit the bell.

The drawing shows a side view of a table-bell embodying my design.

15 B is the bell, having a support, D, and base C.
20 A represents an equine animal, standing

underneath the bell, and having a ball, h, attached to his heel.

k represents an owl surmounting the bell. The animal is pivoted to the support of the bell at e, and serves the purpose of a hammer, 25 the portion of the hammer lying within the support being shown by the dotted lines at f. When the rod g is pressed down, the animal kicks up, striking the bell with his heels or the ball h.

25 I claim—

1. The design for a table-bell, substantially as shown and described.
2. The design for a hammer of a table-bell, substantially as shown and described.

EDWARD L. MORRIS.
